UNITED STATES PATENT OFFICE.

JOHN G. BIENIEK, OF CHICAGO, ILLINOIS.

RACKING-MACHINE.

1,098,659.

Specification of Letters Patent.

Patented June 2, 1914.

Application filed September 11, 1911. Serial No. 648,645.

To all whom it may concern:

Be it known that I, JOHN G. BIENIEK, a citizen of the United States, and residing at Chicago, in the county of Cook and State of Illinois, have invented a new and useful Improvement in Racking-Machines, of which the following is a complete specification.

The main objects of this invention are to provide an improved racking machine; to provide a racking machine in which the filling apparatus may be readily brought into and out of operative position with respect to the barrel to be filled; to provide a racking machine having means for automatically operating the filling valve; to provide a racking machine having improved mechanism for indicating that the barrel is filled; to provide a racking machine having improved means for firmly holding the filling apparatus in operative position; and to provide a strong, simple and easily operable device adapted to fill beer barrels with great rapidity.

A specific embodiment of the invention is illustrated in the accompanying drawings, in which—

Figure 1 is a front elevation of a racking machine embodied in this invention. Fig. 2 is an end elevation of the machine. Fig. 3 is a top plan view of the machine. Fig. 4 is a side elevation of the pressure controlling valve. Fig. 5 is a top plan view of the pressure controlling valve. Fig. 6 is a section taken on line 6—6 of Fig. 4. Fig. 7 is a section taken on line 7—7 of Fig. 1 with parts omitted. Fig. 8 is a section taken on line 8—8 of Fig. 9. Fig. 9 is a section taken on line 9—9 of Fig. 8. Fig. 10 is a plan view of one set of the brake mechanisms for the filling apparatus. Fig. 11 is a side elevation of said brake mechanism. Fig. 12 is a fragmentary side elevation of one of the brake lever actuating rods. Fig. 13 is a top plan view of the filling head or block. Fig. 14 is a section taken on line 14—14 of Fig. 13. Fig. 15 is a section taken on line 15—15 of Fig. 14. Fig. 16 is an enlarged, fragmentary horizontal section of the filling head showing the filling valve. Fig. 17 is a plan view of the actuating gland for the operating blade or device for the filling valve. Fig. 18 is a vertical section of said gland. Fig. 19 is a side elevation of the inlet sleeve for the filling head. Fig. 20 is a side elevation of the outlet sleeve for the filling head. Fig. 21 is a section taken on

line 21—21 of Fig. 13 showing the filling indicator for the barrel in side elevation. Fig. 22 is a vertical section of the filling indicator. Fig. 23 is a side elevation of the frame for said indicator. Fig. 24 is a side elevation of the valve sleeve for said indicator.

In the construction shown, a main frame, having a base 1 and end standards 2 and 3, affords a support for the beer tank 4 at a suitable height, and all of which may be of any suitable construction and material. The frame is provided at its top with a front piece or bar 5, on which are forwardly projecting lugs or arms 6 having ball seats therein. The frame 7 for the filling apparatus is preferably rectangular in shape and has a top member 8, a bottom member 9, and end members 10 and 11. On the back of the frame 7, near the top thereof, is a bar 12 to which is secured a rearwardly projecting ball 13 which seats between the lugs 6 and together therewith provides a ball and socket joint from which the filling frame is pivotally suspended to permit it to be turned to various angles to insure the filling apparatus seating squarely on the barrel. Slidably mounted in the top and bottom members 8 and 9 of the filling frame are the supporting rods 14—14 for the filling head or block 15 which is rigidly secured to the lower ends of said rods (see Fig. 1).

The filling head is provided on its top with an externally threaded boss 16 and on its bottom with an internally threaded boss 17, and is provided with a vertical aperture or passage 18 opening through said bosses. Secured in the boss 17 and depending below the same is the outlet sleeve 19 for the beer after the barrel is filled (Fig. 14). A bushing or packing 20 surrounds the lower end of said sleeve 19 and is adapted to fit in the bung hole of the barrel and form a tight joint therewith when the filling head is in operative position on the barrel. Rigidly secured at its upper end in the passage 18 is the inlet sleeve 21, the external diameter of which is less than the internal diameter of the sleeve 19. Said inlet sleeve is adapted to project into the barrel 22 when the filling head is in place, as shown more clearly in Figs. 1 and 2. Projecting rearwardly from the filling head 15 is an apertured boss 23, (Fig. 15) having a conical valve seat 24 at its inner end from which

passages 25 lead to the passage 18 above the sleeve 21. Within said boss is a ball valve 26 having a stem 27 projecting into the passage 18. A spring 28 bears against the valve 26 and against a flange 29 in the boss and normally acts to hold the valve in closed position. A pipe 30 having a valve 31 therein, leads from the tank 4 and is connected to the boss 23. A supply pipe 32, for the tank 4, 10 leads from the beer vats, not shown, to the tank, and is provided with a valve 33 (Fig. 3).

For the purpose of automatically opening the valve 26 when the head 15 is seated on the barrel, and for closing the valve when the barrel is filled and before the removal of said head, a cylinder 34 is mounted on the top of the frame 7 (Figs. 1 and 2) and the piston therein is provided with a piston rod 35 which extends downwardly through a bar 36 rigidly secured to the guide rods 14, and a bar 37 which is slidably mounted on said rods is attached to said piston rod 35 at the lower end thereof. A nut 38 is carried on the piston rod and bears against the top of the bar 37, and rotatively mounted on the piston rod beneath said bar 37 is the coupling 39. Said nut and coupling cause the bar 37 to travel with the piston rod. 25 The coupling 39 is flattened on two opposite sides to fit into an elongated aperture 40 in the bottom member 9 of the filling frame 7 when the piston rod is at the lower limit of its movement. Rigidly secured in said coupling and extending downwardly therefrom through the filling head is the spiral blade or valve operator 41, which when in operative position bears with one edge against the stem 27 of the valve 26 and holds 30 said valve in open position, as shown more clearly in Figs. 14, 15, and 16. For the purpose of rotating said blade into and out of operative position an actuating gland 42 (Fig. 14) is mounted in the boss 16 and is 35 provided with an elongated slot 43 through which the blade passes. Beneath said gland is a packing 44 and a follower or nut 45 is screwed on the boss 16 and bears on said gland with sufficient force normally to hold 40 the gland from rotation but to permit it to rotate slightly when the blade is held from rotation by reason of the coupling 39 being in the aperture 40.

Mounted on the end member 11 of the frame 7 is the controlling valve 46 of the same construction as that shown in my co-pending application for patent on valve, filed July 5, 1911, Serial No. 636,946.

A main pressure pipe 47 leads from any 60 suitable source of air pressure and a pipe 48 leads therefrom and opens into the top of the beer cylinder 4 to exert air pressure on the beer in the tank (Fig. 3). A flexible pipe 49 leads from the pipe 47 and is connected with the port 50 of the valve 46. A

pipe 51 leads from the port 52 of said valve 46 and opens into the top of the cylinder 34 to admit pressure to force the piston downwardly. A pipe 53 leads from the port 54 of the valve 46 and opens into the bottom of the cylinder to admit pressure to raise the piston. An exhaust port 55 opens from the valve 46 in the same plane as the ports 50, 52, and 54, (Figs. 5 and 6) and the rotative valve closure 56 has transverse passages 57 and 58 therein adapted to be brought into register with said ports. The valve closure has also a passage 59 which connects with a passage 59^a which, when the parts are in the position of Fig. 6, registers with a port 60 in the valve 46. A flexible pipe 61 leads from the top of the tank 4 and connects with the upper end of the passage 59.

The filling head 15 is provided with a laterally directed arm 62 through which extends a passage 63 opening from the space between the sleeves 21 and 19 (Fig. 14). On the outer end of said arm and opening therefrom is an upwardly directed sleeve 64 having a flange 65. A cup nut 66 is mounted on said sleeve and extends above the flange. An indicator frame or skeleton 67 has threaded engagement in said nut, and a globe 68 of glass or other transparent material is carried in said skeleton and rests on 95 said flange. On the top of the skeleton 67 is an apertured boss 69 with which a pipe section 70 is connected. Telescopingly connected with the pipe section 70 is a pipe section 71 which is connected with the port 60 100 of the valve 46 (Fig. 22).

The sleeve 64 extends up into the globe 68 and is provided with small apertures 72. On the top of the sleeve, above said apertures, in an inverted cup shaped hood or 105 deflector 73, and a ball valve 74 is adapted to seat on the top of the sleeve and close the same when beer is not flowing upward through the indicator.

For the purpose of holding the filling head 110 firmly on the barrel during the filling operation, the supporting rods 14 are provided with coarse screw threads or worms 75 at their upper ends, and journaled on the frame member 8 in position for said rods 115 to pass therethrough are friction wheels 76, having pins 77 adapted to travel in said threads. At one side of each friction wheel is pivoted a friction lever 78 adapted to bear at one end against the wheel and hold it 120 from rotation. A spring 79 is connected to the other end of said lever and to a pin 80 on the member 8 and acts to hold the lever in engagement with the wheel. Actuating rods 81 are carried on the bar 36 and extend 125 upwardly through the member 8 beneath the ends of the levers 78 to which the springs are attached. The upper end 82 of each rod 81 is beveled as shown more clearly in Fig. 12, so that when the rod is at the lower limit 130

of its movement it will permit the lever to contact with the wheel 76, but as the rod begins to rise the beveled portion will swing the lever slightly to bring it out of contact with said wheel, and the rod will hold it out of contact until the rod is again lowered.

Carried on the bar 36 and extending downwardly therefrom are the spring clamps 83 adapted, when the piston rod 35 10 has been raised sufficiently to bring the blade 41 out of contact with the valve stem 27, to grip the bar 37 which is caused to move upwardly, Fig. 1, and bear against the bottom of the bar 36 which is bolted or riveted to rods 14; hence, the upward movement of 15 the piston rod 35 beyond a certain distance will elevate the rods 14 and the parts secured thereto.

The operation of the construction shown 20 is as follows: The beer tank 4 is preferably maintained about three fourths full of beer, and the air from pipe 47 passes through pipe 48 and exerts pressure on the beer. When the parts are in the positions shown in Figs. 25 1, 2 and 3, the filling valve 26 is held open by the blade 41 and beer flows from the tank to the barrel. While the beer is entering the barrel the air in the barrel can escape through arm 62, pipe sections 70 and 71, 30 ports 60 and 59 of the valve 46, and pipe 61 to the tank. In this position of the valve 46, pressure passes through pipe 49, through the ports 50 and 52 of the valve, and through pipe 51 to the upper end of the cylinder 34 35 to hold the filling apparatus on the barrel. When the filling head is on the barrel the rods 81 are retracted from the levers 78 and said levers acting on the friction wheels 76 prevent the head from rising. As the beer 40 enters the barrel it passes through the passages 25 of the head 15 and strikes against the blade 41 and runs down into the barrel, thereby washing the blade and keeping it in a sanitary condition. As the barrel becomes 45 filled the beer enters the passage 63 and into the indicator globe 68 so that the operator may see that the barrel is filled and close the valve 46. The valve 46 may be operated by a wrench (not shown) which is adapted 50 to fit over the squared-off end shown in Fig. 5. If the valve is not immediately closed the beer may rise in the pipes 70, 71 and 61 to the level of the beer in the tank, when the flow will cease. The operator now shifts 55 the valve closure 56 of the controlling valve 46 a partial turn to the right to bring the passage 58 into registration with the ports 50 and 54 to permit air to pass through the pipe 53 to the lower end of the cylinder, and 60 at the same time to bring the passage 57 into registration with the ports 52 and 55 to permit exhaust from the upper end of the cylinder 34. This movement of the closure 65 also moves the passage 59 out of register with the port 60, thereby preventing back

flow through the passage 63 when the filling head is removed from the barrel. As the air enters the lower end of the cylinder 34 the piston rod 35 is raised, and when the coupling 39 is withdrawn from the aperture 40 the gland 42 rotates the blade 41 to bring it out of contact with the valve stem 27 and the valve 26 closes. Further upward movement of the rod causes the bar 37 to lock in the clamps 83 and then the filling head 15 is lifted clear from the barrel, and the barrel may be removed and an empty one inserted in its place. Further movement of the closure 56 in the same direction brings the passage 58 into registration with the ports 54 and 55, and the passage 57 into registration with the ports 50 and 52, thereby reversing the motion of the piston and of the piston rod 35 and seating the filling head on the empty barrel, and after the head is seated further downward movement of the piston brings the blade 41 into contact with the valve stem 27 and opens the valve 26, and as the coupling 39 again enters the aperture 40 the blade is held from rotation in operative position and the gland 42 will turn slightly if necessary, due to the curvature of the blade. After the head is seated on the barrel a quick turn of the valve closure 56 in either direction brings it back to its normal or original position and the beer is blown from the indicator and its pipe connections into the barrel, and the air in the barrel is equalized with that in the tank 4. After the valve closure 56 has been turned to close the port 60, the beer in the indicator and its pipe connections will be held from dripping from the passage 63, since the ball 74 closes the top of the valve sleeve 64, thereby restricting the passage, and since no air can enter the connections above the beer.

When the parts are in the positions shown in Figs. 1, 2, and 3, the beer from the vat 4 will flow downwardly through pipe 30, which pipe is connected to the boss 23, said boss, as will be evident from Figs. 14 and 16, being horizontally disposed. The beer passes through said boss, thence through the passages 25 and into the passage 18. As the beer makes its exit from the mouths of passages 25, it will strike the blade 41, and then the beer will flow along said blade, which, as shown in Fig. 1, projects for some distance into the inside of the barrel. Said blade, therefore, reduces or overcomes entirely the natural tendency of the beer to foam and froth and causes the beer to pass from the pipe 30 into the barrel in a substantially solid stream, thus enabling the user of this invention to dispense entirely with the tube or pipe which leads from the filling-head or filling-valve of most other racking machines to the bottom of the barrel. When the blade 41 has been rotated 130

and carried out of engagement with the stem 27, the valve 26 is forced toward the center of the port 18, thus closing the channels or ports 25 through which the beer must pass on its way from the vat 4 to the barrel; and, when the valve 26 has been seated, the flow of beer to the barrel is stopped.

While but one specific embodiment of the invention has been herein shown and described it will be understood that many details of the construction shown may be varied or omitted without departing from the scope of the claims.

I claim:

15. 1. A racking machine, comprising a pivotally supported frame, a filling head adapted to sit on a barrel, supporting rods for the head slidably mounted in the frame and having screw threads at their upper ends, 20 friction wheels journaled on the frame and adapted to be rotated by said threads, friction levers adapted to engage the wheels and hold the head from movement when on the barrel, and means adapted to hold said levers out of contact with the wheels when the head is off the barrel.
25. 2. A racking machine, comprising a pivotally supported frame, a filling head beneath the frame, rods on the head slidably mounted in the frame and having threads at their upper ends, friction wheels journaled on the frame and adapted to be rotated by said threads, spring-controlled levers adapted to engage said wheels when the head is at the lower limit of its movement, a bar supported on said rods, actuating rods on said bar adapted to force the lever away from said wheels when the head is raised, and pressure-operated means adapted to raise and lower the head.

30. 3. A racking machine, comprising a filling head, having a passage therethrough, means movably supporting said head, a valve controlling said passage, a spiral blade slidably mounted in the head, means for moving said blade longitudinally, and means in the head adapted to rotate the blade to open and close the valve.

35. 4. A racking machine, comprising a filling head having a passage therethrough, a valve controlling said passage, a longitudinally movable spiral blade in the head adapted to operate the valve, means in the head adapted to rotate the blade into and out of operative position when the blade is moved longitudinally, and means for moving the blade.

40. 5. A racking machine, comprising a pivotally-mounted frame, a filling head having a passage therethrough, means movably supporting the head on the frame, a valve controlling said passage, a pressure cylinder on the frame, a piston rod projecting from said cylinder, a spiral blade rotatively mounted on the rod and extending into the head, and means in the head adapted to rotate the

blade and operate the valve when the piston rod is moved.

6. A racking machine, comprising a pivotally-mounted frame, a filling head having a passage therethrough, means movably supporting the head on the frame, a valve controlling said passage, a pressure cylinder on the frame, a piston rod projecting from said cylinder, a spiral blade rotatively mounted on the rod and extending into the head, means in the head adapted to rotate the blade and operate the valve when the piston is moved, and means adapted to hold the blade in operative position as the rod approaches the outward limit of its movement.

7. A racking machine, comprising a pivotally-mounted frame, a filling head having a passage therethrough, means movably supporting the head on the frame, a valve controlling said passage, a pressure cylinder on the frame, a piston rod projecting from said cylinder, a spiral blade rotatively mounted on the rod and extending into the head, means in the head adapted to rotate the blade and operate the valve when the piston rod is moved, means adapted to hold the blade in operative position as the rod approaches the outward limit of its movement, and means adapted to connect the rod with the supporting means for the head and raise and lower the head when the valve is closed.

8. A racking machine, comprising a pivotally-mounted frame, a filling head beneath the frame, supporting rods on the head slidably mounted in the frame, a valve in the head, a cylinder mounted on the frame, a piston rod operated from said cylinder, a spiral blade rotatively supported on the piston rod and extending into the head, means in the head adapted to rotate the blade to operate the valve, a bar mounted on the supporting rods, clamps on said bar, means on the piston rod adapted when the piston rod is raised sufficiently to close the valve to engage said clamps and raise the head, and means adapted to hold the blade from rotation at the lower limit of movement of the piston rod.

9. A racking machine comprising a filling-head provided with a substantially vertical passageway, a vat, a pipe leading from the vat and discharging into said vertical passageway substantially at right angles to the axis thereof, and a blade within said vertical passageway, the face of said blade being disposed substantially at right angles to the stream of beer entering from said pipe into said vertical passageway.

10. A racking machine comprising a filling-head provided with a substantially vertical passageway, a vat, a pipe leading from the vat and discharging into said vertical passageway substantially at right angles to the axis thereof, a blade within said vertical passageway, the face of said blade being dis-

posed substantially at right angles to the stream of beer entering from said pipe into said vertical passageway, said blade being partially rotatable, and a valve which is seated or unseated upon the rotation of said blade.

11. A racking machine comprising a filling head having a vertically-disposed passageway therethrough, a vat, a pipe leading from the vat and connected to said passageway, a spiral blade disposed in said passageway and extending therefrom to a point within the barrel, said spiral blade being revolvable within said passageway, and a valve adapted to be operated by the blade.

12. A racking machine comprising a filling head having a substantially vertical pas-

sageway therethrough, a vat, a pipe leading therefrom and connected to said passageway and having entrance thereinto through a substantially horizontal channel, a spiral blade within said vertical passageway extending from a point opposite said horizontal channel to a point within the barrel, said blade being revolvable within said vertical passageway, and a valve adapted to be operated by the blade.

In witness whereof I have hereunto subscribed my name in the presence of two witnesses.

JOHN G. BIENIEK.
